UNITED STATES PATENT OFFICE.

JOSEPH MORHEUSER, OF ST. LOUIS, MISSOURI.

WRENCH.

1,132,483.

Specification of Letters Patent. Patented Mar. 16, 1915.

Application filed June 8, 1912. Serial No. 702,550.

To all whom it may concern:

Be it known that I, JOSEPH MORHEUSER, a citizen of the United States, residing at St. Louis, in the State of Missouri, have invented new and useful Improvements in Wrenches, of which the following is a specification.

The general object of this invention is the provision of an improved wrench which is adapted to be readily and quickly adjusted by the provision of a rotatable handle which is connected in a novel manner to a movable jaw whereby the latter may be adjusted relative to the fixed jaw of the wrench.

15 In carrying out the objects of the invention generally stated above, it will be understood, of course, that the essential features thereof are susceptible to changes in details and structural arrangements, one preferred 20 and practical embodiment being shown in the accompanying drawing, wherein:—

Figure 1 is a side elevation of the wrench constructed in accordance with the invention. Fig. 2 is a vertical longitudinal sectional view thereof. Fig. 3 is an end elevation.

Referring more particularly to the accompanying drawing in which like reference characters designate similar parts, it 30 will be seen that the invention comprises a hollow shank 5 which is provided at one end thereof with a reduced portion to form an opening 6. Extending from the said end of the shank 5 at diametrically opposite sides 35 of the opening 6 are a pair of guide rods 7 which are arranged in parallel relation to each other and which are provided at their outer free ends with the fixed jaw 8 having an opening 9 therein. Slidably mounted 40 upon the guide rods 7 intermediate the shank 5 of the fixed jaw 8 is a movable jaw 10 which is provided with a threaded opening 11 and other openings 12 which are adapted to receive the guide rods 7 whereby the jaw 45 10 may be adjusted back and forth thereon.

A threaded shaft 13 is mounted in the opening 6 of the shank 5 and engages the openings 9 and 11 of the fixed and movable jaws respectively. The shaft 13 is provided 50 for approximately half of its length with a squared portion 14 which is adapted to extend through the shank 5 and receive a rotatable handle 15 thereon, said handle being provided with a square passage extending 55 longitudinally of its entire length and adapt-

ed to receive the portion 14 of the shaft. The handle 15 is provided with a reduced extension 16 which is adapted to project into the shank 5 and said handle is retained in engagement with the shank by means of 60 a nut 17 which is adapted to engage the threaded extension 18 provided at the extreme inner end of the shaft 14.

The fixed jaw 8 has the opening 9 therein intermediate the ends thereof reduced in 65 diameter to form a collar 19. Said collar 19 is adapted to receive the outer smooth extremity 20 of the shaft 13, said extremity being provided with a pair of oppositely 70 disposed laterally projecting lugs 21 which are adapted to engage the outer end of the collar 19 and thus prevent longitudinal movement of the shaft 13 in one direction. It will thus be seen by rotating the handle 15, said shaft will be caused to rotate thus 75 adjusting the movable jaw 10 in either direction.

From the foregoing description taken in connection with the drawing, it will be obvious that the invention contemplates providing a wrench which is simple in construction thus reducing the cost of manufacture of the same to a minimum and which is durable and effective in carrying out the purpose for which it is designed. 80 85

What is claimed is:—

A wrench comprising a hollowed out handle having a shoulder, two rectangular shanks extending forwardly flush with said handle, a rotatable handle of equal diameter with the first mentioned handle, a reduced rotatable sleeve formed upon said second mentioned handle and adapted to fit said hollowed out handle, a longitudinally extending rod having a polygonal part fitting snugly throughout the length of said second mentioned handle at its sleeve, a flange formed upon said rod fitting said hollowed out handle against which said sleeve engages, said rod extending substantially to the end of said shanks and having a threaded stem, a slidable jaw through which said shank passes, said jaw having a threaded bore through which threaded part of said rod passes, a second jaw through which said shanks are passed, said second mentioned jaw having a socket in which the free end of said threaded part bears, a reduced stem formed upon said rod and passing through said second mentioned jaw, the last named 100 105 110

jaw having a second socket, a pin projecting through opposite points of said stem and engaged in said second socket, said rod projecting beyond the opposite end of said rotatable handle, and a head formed upon said rod and bearing against said rotatable handle.

5 Copies of this patent may be obtained for five cents each, by addressing the "Commissioner of Patents, Washington, D. C."

In testimony whereof I affix my signature in presence of two witnesses.

JOSEPH MORHEUSER.
